UNITED STATES PATENT OFFICE.

WILLIAM E. WOOD, OF PHILADELPHIA, PENNSYLVANIA, ASSIGNOR TO THE
PETER L. KRIDER COMPANY, OF SAME PLACE.

DESIGN FOR A SPOON.

SPECIFICATION forming part of Design No. 21,061, dated September 22, 1891.

Application filed July 3, 1891. Serial No. 398,423. Term of patent 3½ years.

To all whom it may concern:

Be it known that I, WILLIAM E. WOOD, a citizen of the United States, and a resident of the city and county of Philadelphia and State 5 of Pennsylvania, have invented a certain new and ornamental Design for Spoons, of which the following is a description.

The design is represented in the accompanying drawing.

- 10 The handle or stem of the spoon is formed by the figure of a North American Indian in full costume. Upon his head are the eagle-feathers, and his hair falls down in plaits along each side of his face. Around his neck 15 is a necklace of bears' claws. His body is naked from the waist up. His legs are incased in fringed breeches. Through a belt around his waist is thrust a tomahawk, and in his right hand is grasped a bow. The figure is 20 represented as standing upon a pile of rocks, underneath which is the head of a buffalo,

and directly underneath this is the bowl of the spoon.

In the drawing, A is the bowl of the spoon; B, the buffalo-head; D, the pile of rocks upon 25 which the figure is represented as standing.

E is the figure of the Indian; F, the eagle-feathers upon his head; G, the plaits of hair; H, the necklace of bears' claws; I, the tomahawk, and K the bow. 30

Having thus described my invention, I claim as new and desire to secure by Letters Patent—

A design for spoon-handles, consisting of an Indian having his head decorated with 35 eagle-feathers and standing erect on a buffalo's head, surmounted by a pile of stones, substantially as shown and described.

WILLIAM E. WOOD.
